[57] CLAIM

The ornamental design for a dart board bezel, as shown.

DESCRIPTION

FIG. 1 is a front elevational view of a dart board bezel showing my new design;

FIG. 2 is a front elevational view of a second embodiment of the design;

FIG. 3 is a side elevational view thereof; and,

FIG. 4 is an underside perspective view of an alternative embodiment of the side elevational view.

FIG. 2

FIG. 3
